[57] CLAIM

The ornamental design for an anti-splash mat for urinal
or the like, as shown and described.

DESCRIPTION

FIG. 1 is a perspective view taken from top, front and
left side of an anti-splash mat for urinal or the like showing
our new design;

FIG. 2 is a front elevational view thereof;

FIG. 3 is a right side elevational view thereof;

FIG. 4 is a rear elevational view thereof;

FIG. 5 is a bottom plan view thereof;

FIG. 6 is a top plan view thereof; and,

FIG. 7 is a left side elevational view thereof.

FIG. 1

FIG. 2

FIG. 3

FIG. 4

FIG. 7

FIG. 6
